Primary Examiner — Garth Rademaker*Assistant Examiner* — Fitzgerald L Butac(74) *Attorney, Agent, or Firm* — King & Schickli, PLLC(57) **CLAIM**

The ornamental design for a housing for an electric motor, as shown and described.

DESCRIPTION

FIG. 1 is a front view of a housing for an electronic motor showing my design;

FIG. 2 is a bottom view; and,

FIG. 3 is a top view.

The broken lines show portions of a housing for an electric motor that form no part of the claimed design.
